UNITED STATES PATENT OFFICE.

PHILIP RICHARDS, OF WILKES-BARRE, PENNSYLVANIA.

FIRE-GRAVE.

SPECIFICATION forming part of Letters Patent No. 269,115, dated December 12, 1882.

Application filed October 24, 1882. (No model.)

To all whom it may concern:

Be it known that I, PHILIP RICHARDS, of Wilkes-Barre, in the county of Luzerne and State of Pennsylvania, have invented certain new and useful Improvements in Fire-Grates; and I do hereby declare that the following is a full, clear, and exact description of the invention, which will enable others skilled in the art to which it appertains to make and use the same, reference being had to the accompanying drawings, which form a part of this specification, and in which—

Figure 1 is a top view of my improved fire-grate. Fig. 2 is a longitudinal vertical sectional view of the same. Fig. 3 is a detail view of the shaking device, and Fig. 4 is a detail view of one of the grate-bars.

Similar letters of reference indicate corresponding parts in all the figures.

My invention has relation to fire-grates; and it consists in the improved construction, combination, and arrangement of parts thereof, as hereinafter more fully described and claimed.

In the accompanying drawings, the letter A represents the fire-place or furnace of a steam-boiler, heating-furnace, or stove, and B is the ash-pit.

C is the front plate of the fire-place, provided with a door of any suitable construction, and opening to the ash-pit under the grate, provided with suitable dampers.

D indicates the grate-bars, which are laid longitudinally in the fire-place, and rest on three sets of rollers, E, F, and G. The grate-bars consist of two flat heads, H and I, the front one, H, of which has a longitudinal slot, J, provided with a cross-pin, K. The upper surface of the central part of the bar consists of a series of V-shaped projections, L, alternately higher and lower, the ends of which project on both sides of the belly-flange M, while their points are pointing rearward. The two heads H and I and a plate, N, on the under side of the belly-flange M rest on the three rows of rollers E, F, and G, which each consists of the rollers O, journaled on the shaft P, which again is journaled in bearings Q, supported under the grate in any desired manner.

The shaking device is fastened to the front plate, C, and protected from the fire and ashes from the fire-place by a plate, R, hinged to the

front plate. It consists in a shaft, S, journaled in bearings T on the front plate, and provided with two bell-crank, U and U'—one at each end. The one arm of the bell-crank U is extended beyond its fulcrum, forming a handle, V. To the ends of the two bell-crank U U' are fastened two rods, W and W', each provided with a series of pitmen or hooks, X, which are hinged upon them and engage the cross-pins K of the grate-bars—one upper and one lower hook—alternately.

It will readily be seen by the foregoing description, taken in connection with the accompanying drawings, that by moving the handle V the hooks will draw every other bar forward and push every other bar back, and by repeating the motion it will shake the ashes from the fire. The ashes will fall down in the ash-pit through the spaces between the projections; and this construction of a grate-bar will also serve to keep it cool and prevent it from burning out or warping, as the air-draft will continually rise between the projections and keep the bar cool. The rollers being journaled on a shaft, which again in its turn is journaled in bearings supporting the three sets of rollers, will assist in their turning easy and prevent their stopping entirely, as if one roller sticks fast to the shaft by expansion of the metal or by dirt or ashes entering its bearings the shaft will turn in its bearings with the roller, or in the case of the shaft getting fast in its bearings the rollers will turn upon it.

The whole shaking device will enable the fireman to shake his fire without opening the door and thus checking the draft from below.

Having thus described my invention, I claim and desire to secure by Letters Patent of the United States—

1. In a fire-grate, the combination of the grate-bars D, mounted on rollers E, F, and G, and having flat heads H and I, and plate N on the belly-flange M, and provided with V-shaped projections L, of alternate height, projecting over the sides of the belly-flange M, with the shaking device, as set forth.

2. In a fire-grate, the combination of the shaking device, consisting of a shaft, S, journaled in bearings T, and provided in each end with a bell-crank, U and U', the bell-crank U having an actuating-handle, V, and both bell-

cranks having rods W W', provided with pit-
men X, fastened in their outer ends, with the
grate-bars D, as set forth.

3. The grate-bar consisting of the heads H
5 and I and belly-flange M, having upward V-
shaped projections, alternating in height and
projecting over its sides, substantially as shown
and described.

In testimony that I claim the foregoing as my
own I have hereunto affixed my signature in the
presence of two witnesses.

PHILIP RICHARDS.
